UNITED STATES PATENT OFFICE.

FRANK C. ANDERSON, OF CINCINNATI, OHIO, ASSIGNOR OF ONE-HALF TO AMERICAN VALVE AND METER COMPANY, OF CINCINNATI, OHIO, A CORPORATION OF WEST VIRGINIA.

SWITCH-STAND.

SPECIFICATION forming part of Letters Patent No. 746,911, dated December 15, 1903.

Application filed April 21, 1903. Serial No. 153,586. (No model.)

To all whom it may concern:

Be it known that I, FRANK C. ANDERSON, a citizen of the United States, residing at Cincinnati, in the county of Hamilton and State of Ohio, have invented certain new and useful Improvements in Switch-Stands, of which the following is a full, clear, and exact description, reference being had to the accompanying drawings, forming part of this specification.

My invention relates to that class of mechanism for operating switches of railways wherein a target-shaft is provided to carry visible targets for day use and a lantern with colored lights for night use; and it has for its object the provision of simple and efficient means whereby the life of such operating mechanism is greatly prolonged over those now in general use and whereby the danger of breakage to the switch-points is reduced to the minimum.

The novelty of my invention will be hereinafter more fully set forth, and specifically pointed out in the claims.

In the accompanying drawings, Figure 1 is a central sectional side elevation of a switch-stand embodying my invention. Fig. 2 is a plan view of Fig. 1 with the upper part of the housing removed and showing the target-shaft in section. Fig. 3 is a plan view of the operating-gear as shown in Fig. 2, but on an enlarged scale. Fig. 4 is a plan view of the triple switch-throwing crank-arm which forms one of the essential features of my invention.

The same letters of reference are used to indicate identical parts in all the figures.

A represents the two-part housing or box covering the switch-operating mechanism and secured in the usual manner upon the extending ends of the cross-ties B. Suitably journaled in the top of the box A and in the yoke C at the bottom of the box is the vertical target-shaft D, carrying the targets E and having on its upper end the squared portion F, upon which fits the usual varicolored lantern (not shown) for night-signals. Loosely mounted upon the target-shaft D and adjacent to the yoke C is the switch-throwing crank-arm G, which is provided on its upper

face at its center with one member, H, of a positive clutch, the other member, I, being provided upon the operating-gear J and on its under face.

The operating-gear J is rigidly secured to the target-shaft D, preferably by means of a bolt a passing through the upper extension of the hub of the gear J and through the target-shaft D. This connection serves to rotate the target-shaft D when the gear J is rotated, as will be readily understood.

The operating-gear J is preferably made in the form of a double segment, as clearly shown by Fig. 3, with connecting-webs b between the two segments. These webs b serve to brace the toothed portions of the gear and also serve the further purpose of allowing the gear J to be made circular in form, so as to completely fill the opening in the lower part of the two-part housing A and prevent stones or snow or other obstructions from entering the box or housing and interfering with the operation of the mechanism, as will be readily understood. The webs b are preferably perforated, as shown in Fig. 3, for the purpose of permitting oil and dust, which will accumulate in the box A, to pass out therefrom.

Meshing with one of the segments of the gear J is a pinion K, suitably secured upon the inner end of a stub-spindle L, to the outer end of which is secured the operating-handle M usual in this class of switch-stands. The stub-spindle L is suitably journaled, as shown in Figs. 1 and 2, through the housing A.

It will be readily seen that by throwing the operating-lever M from one side to the other the stub-spindle L will be rocked, carrying with it the pinion K, which, meshing with the gear J, will revolve it, and with it the target-shaft D and the switch-throwing crank-arm G, which being connected by means (not shown) to the point-rails of the switch will throw the switch in either direction, according to the direction of the movement of the operating-handle M.

My purpose in providing two sets of teeth on the gear J is to provide a double life for this gear. When the gear has become worn out on one side from continual use or if some

of the teeth become broken from any cause, it is only necessary to remove the bolt *a* which secures the gear *J* upon the target-shaft *D* and revolve the gear upon the target-shaft 5 until the set of teeth upon the opposite side of the gear come into mesh with the pinion *K*, when the bolt *a* may be replaced, which will restore the switch-stand to its operative condition. When this is done, the positive 10 clutch *H I*, between the gear *J* and the switch-throwing crank-arm *G*, will permit of the adjustment of the gear *J* without disturbing the adjustment of the crank-arm *G* with relation to the point-rails of the switch.

15 As will be seen by reference to Fig. 4, I construct the switch-throwing crank-arm *G* in a manner not usual in this class of switches, and for this reason: Ordinarily these crank-arms are provided with either one or two ex- 20 tensions *c*, provided with openings *d* for the passage of the bolt which connects the switch-throwing crank-arm to the connecting-bar which operates the switch, and these extensions *c* are generally made of such size as to 25 be non-breakable, and in case a train runs through a switch while locked the usual result is a breakage of the point-rail of the switch or a breakage of the operating mechanism of the switch-stand, while in my present construction neither of these results will 30 follow should a train run through the switch while locked, as I construct the extensions *c* in the manner shown in Fig. 4 with a reduced area of metal between the opening *d* and the 35 clutch member *H*. This construction results in weakening the crank-arm *G* to such an extent that it will break before any of the other parts of the switch-stand or of the switch, while leaving it strong enough for the ordinary 40 operation of the switch, and as I provide three of these extensions *c* on the crank-arm *G* it will be readily seen that the switch may be improperly run through three times before it becomes necessary to restore any of 45 its parts, as the only thing necessary to be done is the loosening of the upper part of the housing and raising the same a sufficient distance to permit of the disengagement of the clutch *H I*, when the crank-arm may be re- 50 volved to the proper position, it being loose upon the target-shaft *D* and the clutch re-engaged, when a new arm will be brought into proper working position and be connected to the point-rails in the usual manner, the 55 position and spacing of the clutch members being such that when the clutch is locked the extensions *c* of the crank-arm *G* are always in proper working position.

If preferred, notches *e* may be cut in the 60 reduced portion of the extensions *c* to insure their breakage under unusual strain.

I have described in the early part of this specification one manner of shifting the gear *J* so as to bring a new set of teeth into operating position by removing the bolt *a*, then 65 shifting the gear, and replacing the bolt. Another method of shifting this gear where it is constructed as shown in Fig. 3 is by simply loosening the two-part housing and raising the same a sufficient distance to permit of the disengagement of the clutch *H I* and then revolving the target-shaft one-half turn, which will bring the targets to the same positions they occupied before and bring a new set of teeth on the gear *J* into mesh with 70 the pinion *K*, when the box *A* may be again put together and the clutch be reengaged and the switch restored to its working position, as will be readily understood.

Having thus fully described my invention, 80 I claim—

1. In switch-operating mechanism, the combination of a vertical target-shaft, an operating-gear fast thereon and adapted to be operated by hand, a switch-throwing crank-arm 85 loosely mounted upon said vertical target-rod, and a positive clutch interposed between said operating-gear and said switch-throwing crank-arm, substantially as described.

2. In switch-operating mechanism, the combination of a vertical target-shaft, an operating-gear adjustably secured thereon, a hand-operated pinion meshing with said operating-gear, a breakable switch-throwing crank-arm loosely mounted upon said target-shaft, and 95 a positive clutch interposed between said operating-gear and said switch-throwing crank-arm, substantially as described.

3. In switch-operating mechanism, the combination of a vertical target-shaft, an operating-gear adjustably secured thereon, a hand-operated pinion meshing with said operating-gear, a three-arm breakable switch-throwing crank-arm loosely mounted upon said target-shaft, and a positive clutch interposed between 105 said operating-gear and said switch-throwing crank-arm, substantially as described.

4. In switch-throwing crank-arms for switch-stands, the combination with a hub 110 portion of an extension thereon provided with an opening for connection with the point-rails of the switch, a reduced area of metal between said hub portion and said extension, whereby when an unusual strain is put upon 115 said crank-arm, the same will break at said reduced portion, substantially as described.

FRANK C. ANDERSON.
